UNITED STATES PATENT OFFICE.

ALEX LA BELL, OF DETROIT, MICHIGAN.

DESIGN FOR A FUNERAL-CAR BODY.

43,821.

Specification for Design.

Patented Apr. 8, 1913.

Application filed October 17, 1912. Serial No. 726,377. Term of patent 7 years.

To all whom it may concern:

Be it known that I, ALEX LA BELL, a citizen of the United States, residing at Detroit, in the county of Wayne and State of Michigan, have invented a new, original, and ornamental Design for Funeral-Car Bodies, of which the following is a specification, reference being had to the accompanying drawing, forming part thereof.

The figure is a side elevation of a funeral

car showing my new design of a funeral car body.

I claim—

The ornamental design for a funeral car body as shown.

ALEX LA BELL.
